S. R. SEIBERT.

Surveying Instruments.

No. 25,678.

Patented Oct. 4, 1859.

UNITED STATES PATENT OFFICE.

SAMUEL R. SEIBERT, OF MUNISING, MICHIGAN.

SURVEYING INSTRUMENT.

Specification of Letters Patent No. 25,678, dated October 4, 1859.

To all whom it may concern:

Be it known that I, SAM'L R. SEIBERT, of Munising, in Schoolcraft county, State of Michigan, have invented a new and Improved Method of Constructing Surveying Instruments; and I do hereby declare that the following is a full and exact description of the same, reference being had to the accompanying drawings, and to the letters 10 of reference marked thereon, making a part of this specification, in which—

Figure 1 is a perspective general view; Fig. 2, the base view of lower Plate No. 1 in Fig. 1; Fig. 3, side view of Y's or telescope supports; Fig. 4, a vertical view of Y's or telescope supports; Figs. 5 and 6, different base views of clamping pinion; Fig. 7, side view of clamping pinion.

The nature of my invention consists in 20 constructing the supports of the telescope in such a manner as to allow it to be revolved upon its axis and be brought to bear upon any object appearing between the zenith and the horizon. The construction also 25 admits of the use of a magnetic needle and of an improved sextant in principle the same as invented by William Burt. This mode of supporting the telescope makes it an important check upon the sextant, for 30 instance, in ascertaining by the sextant the latitude of any position. The image of the sun is brought upon the plate of the limb H, Fig. 1. It should be also upon the cross hairs in the telescope at the same time, so 35 that when the sextant reads the meridian passage of the sun the telescope can be used to ascertain its correctness and the altitude read by the vertical circle. It can also be used at night in connection with the moon 40 and his culminating stars, producing the same results. In short the combination of magnetic needle sextant and telescope furnish unmistakable guides for the running of lines, determining of latitudes, determining 45 time and the variation of the magnetic needle from a true meridian. The clamping pinion by which the different limbs are moved and clamped will be found fully described and referred to by letter.

50 To enable others skilled in the art to make and use my invention I will proceed to describe its construction and operation.

I construct the lower Plate No. 1, Fig. 1, also shown at Fig. 2 in the accompanying drawing, so as to admit of the Y's or supports of telescope of which Figs. 3 and 4 are representations, being permanently attached to said lower plate. As the lower

extremity of said Y's or supports have what is termed a wide base, it will be perceived 60 that when they (the supports of telescope) are attached to the lower plate they form an immovable construction of each support and when combined by the axis A of telescope R in Fig. 1 obtain a permanency seldom, if ever, found in portable instruments. I construct my supports or Y's, Figs. 3 and 4, so as to throw the center of upper part of said Y's or supports sufficiently beyond the upper Plate B in Fig. 1 as to admit of the 70 telescope when resting in said Y's or supports to be revolved on its axis from a horizontal to a vertical position. I construct my clamping pinion as represented in the accompanying drawing, in Figs. 5 and 6 as 75 base views and Fig. 7 as a side view. The center piece C in Figs. 5, 6, and 7, to the lower extremity of which are permanently attached the cogs L, can be constructed round and a steady pin D in Fig. 5 permanently soldered to sliding milled head E, Fig. 7. It can also be angular, so as to prevent it (the said sliding milled head) from turning without carrying this center piece C with it. The upper extremity of this 80 center piece C in Figs. 5, 6, and 7 has a thread cut upon it, on which is screwed the milled bur F, Fig. 7. By screwing this milled bur F upon the sliding milled head E, Fig. 7, it forces the sliding head upon or 85 against the plate G Fig. 7, in which cogs are also cut or which represents part of the circle upon which the limb is usually slid. H and I, Fig. 1, represent the segment of a circle (usually called the declination arc 90 and divided into parts of degrees) and limb as they are generally constructed. The clamping pinion is not visible, as it appears behind said arc H. This clamping pinion can be applied to any instrument or place 100 where a limb with vernier or index attached is to be slid or moved for the purpose of reading different angles.

What I claim as my invention, and desire to secure by Letters Patent, is— 105

1. Constructing the Y's, or supports of the telescope in a surveying instrument as set forth.
2. Also constructing a clamping pinion in the manner and for the purposes as herein described.

SAML. R. SEIBERT.
